OIL SEAL

Filed July 26, 1933

UNITED STATES PATENT OFFICE

1,962,398

OIL SEAL

Raymond P. Lansing, Montclair, N. J.

Application July 26, 1933, Serial No. 682,350

22 Claims. (Cl. 123—179)

This invention relates to oil seal means, and more particularly to means for preventing the seepage of oil into the housings of engine starting devices.

5 It has heretofore been proposed to provide starters of the inertia type for internal combustion engines. As is well understood in the art, the operation of starters of this character depends upon storage of energy in a flywheel 10 which is brought up to high speed by manual or power operation, the high speed of the flywheel being attained through multiple gearing positioned in the starter housing. The stored energy in the flywheel is employed at the will 15 of the operator in cranking the engine.

For the most part inertia starters are attached to the rear end of the engine crank case with the starter jaw in alinement with a jaw formed on the engine crank shaft or an 20 extension thereof, the starter jaw being moved into engagement with the engine crank shaft jaw to transfer the energy of the flywheel to the crank shaft. It is highly desirable to prevent the seepage of oil from the engine crank 25 case into the starter housing, since this oil renders it extremely difficult, and in certain instances impossible, to bring the flywheel up to the desired speed of rotation, due to the braking effect of the oil which frequently becomes 30 highly viscous.

Accordingly, it is an object of the present invention to provide a novel oil seal for preventing lubricating oil in the engine crank case from seeping into the starter housing.

35 Another object of this invention is to provide novel oil seal means embodying a baffle plate which acts as a pilot to facilitate mounting the starter on the engine crank case.

Other objects include the provision of a light, 40 durable, simple and inexpensive oil seal which may be readily installed and which is so constituted that the parts may be readily renewed without disassembly of the starter mechanism.

One embodiment of the present invention is 45 disclosed in the accompanying drawing, wherein like reference characters refer to like parts throughout the several views. It is to be expressly understood, however, that the drawing is for purposes of illustration only and is 50 not designed as a definition of the limits of the invention, reference being had for this purpose to the appended claims.

In the drawing—

Fig. 1 is a perspective of an inertia starter 55 provided with one embodiment of an oil seal

formed in accordance with the present invention;

Fig. 2 is a detail, sectional view of the means constituting the preferred form of the oil seal;

Fig. 3 is an axial sectional view illustrating 60 the oil seal mounted in cooperative relation with a starter of the type illustrated in Fig. 1; and

Fig. 4 is a view in perspective illustrating the means by which pressure is exerted to maintain 65 an effective seal.

In the form shown, the starter comprises a housing constituted by an inner section 4 provided with a flange 4a that is adapted to be secured by screws 5 to an engine crank case 6. The housing also includes an outer section 7 70 that is removably attached to the outer face of section 4, as by means of screws 8. Rotatably mounted on ball bearings 9 mounted in a hub 10 formed in the outer face of housing section 7 is a flywheel 11 that is adapted to be rotated at 75 high speed. A light, sheet-metal cover 12 encloses and protects the flywheel and is removably secured to the outer face of housing section 7 in any suitable manner.

Either power or manual means may be provided for storing energy in the inertia member, i. e., for rotating flywheel 11 at high speed. As shown, the starter includes manual means only for this purpose, said means comprising a rotatably mounted cranking shaft 13 which ex-

80 tends substantially at right angles to the axis of rotation of the flywheel, and which carries on the end thereof that projects exteriorly of the housing, a member, such as pin 14, to receive a hand crank (not shown) for rotating said shaft. Rigidly secured to the inner end of shaft 13 is a bevel gear 15 that meshes with 85 a bevel gear 16 which is rigidly attached to the outer end of a sleeve 17 drivably connected in any suitable manner on the outer face of the closed end of barrel 19 are three planetary gears 21, 90 one of which is shown in section, the other two being omitted in the drawing to avoid obscuring the showing of the adjacent parts. The gears 21, which are angularly spaced at 120 degree intervals relative to the closed end of barrel 19, are surrounded by and in mesh with an internal gear 22 which is rigidly attached to housing section 4 as by means of studs 23. The planetary gears also mesh with a sun gear 24 95 which is rotatably mounted on sleeve 17 and 100

105

110

which is preferably formed integrally with an internal spur gear 25. Any rotary movement imparted to barrel 19 acts on the planetary gears 21 and sun gear 24 to rotate the spur gear 25 which meshes with a pinion 26 that is rigidly connected in any suitable manner to a shaft 27. Preferably, the shaft 27 is rotatably mounted in a hub 28 formed in housing section 7. Drivably attached in any suitable manner to shaft 27 closely adjacent pinion 26 is a bell-shaped member 29 which surrounds a portion of hub 28 and which is provided on its larger end with a series of teeth constituting a spur gear 30 that meshes with a pinion 31 formed on a shaft 32 that is keyed to the hub of the flywheel 11. Rotation of the cranking shaft 13 is transmitted through the gearing and barrel described above to the flywheel, whereby the flywheel may be rotated at very high speed.

After sufficient energy has been stored in the flywheel 11 this energy may be transmitted through a starter jaw or driving member 33 to a corresponding jaw 34 provided on the crank shaft of the engine or an extension thereof, means being provided, and operable at the will of the operator, to move starter jaw 33 longitudinally into meshing engagement with jaw 34. The energy stored in the flywheel is now effective to crank the engine. As shown, this means comprises a threaded shaft 35 which is mounted for rotary and longitudinal movement within an interiorly threaded nut 36 positioned in barrel 19 and drivably attached thereto in a manner to be described hereafter. The engine end of shaft 35 is exteriorly splined to receive the splined portion 33a of clutch jaw 33. Extending longitudinally and slidably through threaded shaft 35 and through a central opening in the hub of jaw 33 is a rod 37 which extends outwardly to a point closely adjacent the pinion 31. Intermediate its ends, rod 37 is provided with a shoulder which is normally in abutting engagement with the outer end of threaded shaft 35. Interposed between the hub of jaw 33 and shaft 35 and surrounding rod 37 is a coil spring 38 which yieldingly resists movement of jaw 33 towards said threaded shaft. The clutch jaw is maintained in operative engagement with rod 37, as by means of a nut 39, threaded onto the outer end of said rod and normally in engagement with the hub of the starter jaw. Pivots connected to the outer end of rod 37 is a lever arm 40 rigidly attached to a rock shaft 41 (Figs. 1 and 4) which extends outwardly through housing section 7 and has rigidly connected thereto a bell crank lever 42. A spring 42a is coiled about the rock shaft 41 with one end abutting the housing and the other end turned to engage the arm 40 and thus exert a constant pressure tending to hold the rod 37 in the position indicated in Fig. 1, in which position the rearward surface of the jaw 33 presses upon the oil sealing parts (to be further described) and thus insures, in conjunction with the cooperating means (also to be described) the maintenance of an effective sealing action. The spring 42a has the additional function of resisting any tendency of the jaw 33 to move toward the engine member 34. When it is desired to effect such a movement, in order to transmit starting torque to the engine crank shaft, the operator must exert, through the bell crank lever 42, a force sufficient to overcome the resistance of the spring 42a.

When this is done, rod 37 is moved to the left, as viewed in Fig. 3, and jaw 33 is moved into meshing engagement with the jaw 34. The energy in the flywheel is now effective to start the motor.

Preferably a yielding driving connection is provided between the starter gearing and jaw 33 to prevent any damage to the parts which might result from an instantaneous application, to the engine crank shaft, of the large amount of energy stored in the flywheel. As shown, this yielding connection is constituted by a multiple disk clutch comprising a plurality of friction disks 43, certain of said disks being splined to the inner surface of barrel 19 and the remaining portion of said disks, which are in interleaving relation with the first named portion, are splined to the outer surface of the flanged nut 36. The amount of torque to be transmitted by the multiple disk clutch may be varied by means of a plurality of coil springs 44 which are adapted to vary the frictional engagement of the clutch disks and which are maintained in operative engagement with said disks by means of an adjusting member 45 which is threaded into the open end of barrel 19.

In starters heretofore provided the seepage of oil from the engine crank case into the starter housing has rendered the operation of the starting mechanism extremely difficult, and in certain instances impossible. Various oil seals have heretofore been proposed to overcome the above difficulties, but all have proven unsatisfactory. For example, it has been proposed to provide felt washers between the central portion of 110 rotating barrel 19 and the housing section 4. Such an arrangement has been unsatisfactory, however, due to the fact that barrel 19 rotates during the time that energy is being stored in the flywheel and during the time that the flywheel is imparting starting energy to the motor, and consequently the felt washers wear very rapidly and lose their effectiveness.

In accordance with the present invention, novel means are provided for preventing seepage of oil around the barrel past the hub portion of jaw 33, and past the opening in the hub of jaw 33 through which rod 37 slidably extends. For this purpose there is fitted over the engine end of the starter a baffle plate 125 46 which, in the form shown, is approximately bell-shaped and which may be pressed from sheet-metal. The larger or outer end of the baffle plate is provided with a laterally projecting flange 47 adapted to abut against the flange 4a of the inner housing section, the flange 47 being provided with openings which align with the openings formed in flange 4a to receive screws 5. Thus, when the starter is mounted on the engine crank case, flange 47 is clamped by screws 5 between flange 4a and the crank case. Closely adjacent flange 47, the baffle plate is preferably provided with an annular enlargement 48 to form a shoulder 49 that constitutes a retainer for the races of ball bearing 20a. The central portion 50 of the baffle plate is substantially cylindrical in form, but intermediate said cylindrical portion and the inner end 51 there is provided a somewhat conical portion 52 and an inwardly extending and substantially flat portion 53 that constitutes a supporting surface for the outer half of an annular or ring-shaped oil seal washer 54. Preferably, this oil seal washer is formed of flexible material such as leather or the like.

Suitable means are provided for securing the washer to portion 53 of the baffle plate. In the form shown, a plurality of rivets 55 are employed for this purpose and preferably said 5 rivets extend through the baffle plate, the washer and a narrow ring 56 which extends around the face of washer 54 closely adjacent the periphery thereof. Washer 54 is provided with a central opening through which extends the hub portion 10 33a of the starter jaw and this opening is of a less diameter than the inner diameter of the curved end 51 of the baffle plate.

Means are provided for normally holding the inner portion of washer 54 tightly against the inner face of the enlarged head of said starter 15 jaw whereby seepage of oil past the central opening in the washer is prevented. For this purpose a tubular sleeve 57 is slidably mounted on portion 33a of the starter jaw, the outer 20 end of said sleeve having abutting engagement with the flange of nut 36. Preferably the inner end of sleeve 57 is provided with a small flange which has abutting engagement with a ring 58 that is preferably formed of metal, said ring 25 and sleeve being adapted to bend the inner portion of the washer 54 outwardly out of the plane of the periphery of said washer and to hold said inner portion tightly against the enlarged head of jaw 33, whereby seepage of oil from the 30 engine crank case around the starter jaw is prevented.

In order to prevent seepage of oil through the central opening in the hub of jaw 33 there are provided two or more washers 59 and 60 which 35 are mounted on rod 37 and which are tightly held against the hub portion of jaw 33 by means of spring 38. Preferably the washer 60, which is engaged by the inner end of spring 38, is formed of metal and the washer 59 is preferably 40 formed of a flexible material, such as leather or felt.

The baffle plate 46 constitutes a pilot for facilitating the mounting of the starter on the engine crank case. It completely covers the portion of the starter protruding into the crank case and protects the starter from oil splash. This plate also constitutes a guard for the elements of the starter which project into the crank case. Normally the starter jaw is housed 50 within the reduced end of the baffle plate and coacts with the ring 58 and sleeve 57 to clamp washer 54, whereby an oil seal is formed. The jaw 33 is free to be moved longitudinally by means of rod 37 into meshing engagement with jaw 34. In the event that it is desired to replace washers 54 and 59, it is unnecessary to disassemble the starter mechanism, it being only necessary to remove nut 39 and jaw 33. The means constituting the oil seal are light in 60 weight, durable and inexpensive.

This application is a continuation in part of my former application Serial No. 257,489, filed February 27, 1928.

While one particular form of starting apparatus has been described in detail, it is to be understood that the invention is not limited thereto, since the oil seal means is adapted for use with various other forms of starters, inertia or otherwise. The invention is capable of receiving a 65 variety of mechanical expressions, some of which will readily suggest themselves to those skilled in the art, while changes may be made in the details of construction, arrangement and proportion of parts, without departing from the 70 spirit of the invention. For example, the con- 75

tour of the baffle plate may be varied to conform with the type of starting mechanism to which it is applied. The member 54 may be of leather or other suitable material. Reference is therefore to be had to the claims hereto appended for a definition of the limits of the invention. 80

What is claimed is:

1. In combination with an engine crank-case, a starter having a housing, a portion of said starter protruding into said crank-case, oil seal 85 means for preventing seepage of oil from the crank case into the starter housing, said means including a baffle plate covering the portion of the starter within the crank-case, and a flexible member carried by the inner end of said plate and adapted for engagement with a movable element of the starter. 90

2. In combination with an engine, a starter embodying a member movable into and out of engagement with a member of said engine, a portion of said starter extending into the crank-case of said engine, oil seal means for preventing seepage of oil from said crank-case into the 95 starter comprising a baffle plate for enclosing the portion of the starter extending into the crank-case, said plate having an opening through which the first named member is freely movable, and a flexible member carried by said plate and having engagement with said movable starter member. 100

3. Oil seal means for a starter of the type embodying a longitudinally movable driving member, comprising a baffle plate for enclosing a portion of said starter, and a flexible washer carried by said plate, said washer surrounding 110 and having slidable engagement with said driving member.

4. An oil seal for a starter of the type embodying a longitudinally movable driving member, comprising a baffle plate covering a portion 115 of said starter and having an opening therein through which the driving member is movable and a flexible member secured to said plate and having engagement with said driving member.

5. An oil seal for a starter of the type embodying a longitudinally movable driving member, comprising a baffle plate, a leather washer carried thereby, and means for normally holding a portion of said washer in close engagement with said driving member. 125

6. An oil seal for a starter of the type embodying a longitudinally movable driving member, comprising a baffle plate for enclosing a portion of said starter, a flexible member carried by said plate and having a portion adapted to engage said driving member, a member having engagement with said flexible member, and a sleeve engaging said last named member. 130

7. An oil seal for a starter of the type embodying a longitudinally movable driving member, comprising a baffle plate enclosing a portion of said starter and having an opening through which said driving member extends, a flexible member carried by said plate and having a portion projecting into said opening, a sleeve washer 140 mounted on said driving member and adapted to engage said flexible member, and a sleeve having slidable engagement with said driving member and abutting engagement with said sleeve washer. 145

8. An oil seal for a starter comprising a baffle plate having an opening therein, a flexible member carried by said baffle plate and having a portion projecting inwardly adjacent said opening, and rigid means for bending the central 150

- portion of said flexible member outwardly towards said opening.
9. An oil seal for a starter of the type embodying a longitudinally movable driving member, comprising a metal baffle plate enclosing a portion of said starter and having an opening therein, a flexible washer secured adjacent its outer edge to the baffle plate and extending inwardly therefrom, the inner portion of the washer being adapted to engage said driving member, a washer having engagement with the flexible washer, and a sleeve slidably mounted on the driving member and engaging said second named washer.
15. 10. An oil seal for a starter comprising a baffle plate enclosing a portion of the starter, and a flexible member carried by the plate and adapted to coact with said baffle plate for excluding oil from said starter.
20. 11. An oil seal for a starter of the type embodying a longitudinally movable driving member and a rod slidably extending through said driving member for moving the same, said oil seal comprising a baffle plate covering a portion of said starter, a flexible member carried by said baffle plate and adapted to engage said driving member, means for maintaining said flexible member in engagement with said driving member, and means surrounding said rod and engaging said driving member for preventing seepage of oil.
25. 12. In combination with an engine and a starter mounted on the crank-case of the engine and having a portion extending into said crank-case, a baffle plate clamped between said crank-case and said starter, said baffle plate covering the portion of the starter extending into the crank-case, and means carried by said baffle plate and coacting therewith to prevent seepage 40 of oil from the crank-case into the starter.
30. 13. In combination with an engine and a starter mounted on the crank-case of the engine, said starter and a portion thereof extending into a said crank-case and being provided with a longitudinally movable driving member, a baffle plate clamped between the crank-case of the engine and the starter, the baffle plate covering the portion of the starter extending into the crank-case, a flexible member carried by the baffle plate and having engagement with said driving member, and means having engagement with said driving member for flexing the flexible member.
35. 14. In combination with a starter of the type embodying a longitudinally movable driving member, the starter having a portion thereof projecting into the crank-case of the engine on which it is mounted, a baffle plate surrounding the projecting portion of said starter, a flexible washer carried by the baffle plate and having engagement with said driving member, a second flexible member and means for maintaining said last named flexible member in engagement with the driving member, said plate, washer, and flexible member being adapted to prevent seepage of oil from the engine crank-case into the starter.
40. 15. In combination with a starter of the type embodying a longitudinally movable driving member adapted to be driven through a clutch, the starter having a portion thereof projecting into the crank-case of the engine on which it is mounted, a baffle plate surrounding the projecting portion of said starter and having an enlarged portion adapted for use as a retainer
45. for portions of said starter, a flexible washer carried by the baffle plate and having engagement with said driving member, a flexible member surrounding said driving member, and means for maintaining said last named flexible member in engagement with the driving member, said plate, washer, and flexible member adapted to prevent seepage of oil from the engine crank-case into the starter.
50. 16. In combination with a starter, a longitudinally movable driving member and a rod slidably extending through said driving member, a starter having a portion thereof projecting into the crank-case of the engine on which it is mounted, a frusto-conical shaped baffle plate surrounding said projecting portion and having a portion adapted to maintain portions of the starter in proper position, a flexible washer carried by the baffle plate and having engagement with said driving member, a flexible member surrounding said rod, means for maintaining said last named flexible member in engagement with the driving member, and means carried by said driving member for maintaining said flexible washer in engagement with said plate, washer, and flexible member being adapted to prevent seepage of oil from the engine crank-case.
55. 17. In combination with a crank-case of an engine to be started and a starter of the type embodying a longitudinally movable driving member, of an oil seal comprising a frusto-conical shaped member having a central opening therein for receiving said driving member, a flange terminating at the larger end of the conical shaped member for engagement with said starter and crank-case, an intermediate portion enclosing a portion of said starter, the last said portion extending into said crank-case, a flexible washer carried by said conical shaped member, said washer surrounding and having sliding engagement with said driving member, and means for moving said washer to operable position, the said means carried by the said driving member.
60. 18. In combination with an engine crank-case, a starter having a housing supported on said crank-case, and oil seal means for preventing seepage of oil from the crank-case into the starter housing, said means including a plate surrounding the engine engaging end of the starter, and means cooperating with said plate to seal the entire space between said plate and the moving elements of the starter.
65. 19. In combination with an engine crank-case, a starter having a member movable into and out of engagement with the engine crank-shaft, a housing surrounding said engine engaging member and supported on said crank-case, and oil seal means for preventing seepage of oil from the crank-case into the starter housing, said means including a plate surrounding the engine engaging member, and means cooperating with said plate to seal the entire space between said plate and engine engaging member.
70. 20. Oil seal means for a starter of the type embodying a longitudinally movable driving member, comprising a baffle plate for enclosing a portion of said starter, and a flexible washer carried by said plate, said washer surrounding and having slidable engagement with said driving member, and means acting constantly upon said driving member to hold the latter firmly in contact with said flexible washer and thereby insure the effectiveness of the sealing action.
75. 21. Oil seal means for a starter of the type

- embodying a longitudinally movable driving member, comprising a baffle plate for enclosing a portion of said starter, a flexible washer carried by said plate, said washer surrounding and having slidable engagement with said driving member, and means acting constantly upon said driving member to hold the latter firmly in contact with said flexible washer and thereby insure the effectiveness of the sealing action, said last named means including a rod having one end operatively connected with said driving member, a manually operable shaft operatively connected with its other end to control the longitudinal movement of the rod and driving member, and a spring coiled about said shaft to exert an endwise pressure on said rod and driving member.
22. In combination with an engine crank-case, a starter having a housing supported on said crank-case, an oil sealing means for preventing seepage of oil from the crank-case to the housing, said means including a non-metallic sealing member, an engine engaging member, and means tending to hold said engine engaging member out of engine engaging position, said means also acting to press said engine engaging member against said non-metallic sealing member and thereby insure an effective sealing action. 80
